RAYMOND S. DEVNEY, OF OWENSBORO, KENTUCKY.

MOTOR FOR CHURNS AND THE LIKE.

1,369,888.

Specification of Letters Patent. Patented Mar. 1, 1921.

Application filed May 7, 1919. Serial No. 295,266.

To all whom it may concern:

Be it known that I, RAYMOND S. DEVNEY, a citizen of the United States, residing at Owensboro, in the county of Daviess and State of Kentucky, have invented a new and useful Motor for Churns and the like, of which the following is a specification.

This invention relates to motors and more particularly to power means well adapted for the agitation of the contents of a churn body, although capable of many other uses.

The object is to provide a driving means for churns which may be actuated either by means of a hand-crank or by the power generated by the gravitation of a weight which, by reason of certain speed-increasing gearing, serves to actuate the agitating means within the churn body at increased speed, and at the same time winds up other parts for the immediate application of the weight again, upon the completion of a full downward passage of the same, so that the operation of the motor is practically a continuous one.

A further object is to provide a machine having the above characteristics which may be readily changed for operation by hand or to be operated automatically, and wherein a prime desideratum has been to construct the several parts as economically as possible in order to render the same capable of being manufactured at a low cost.

A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a front elevation of the improved motor for churning, some of the parts being shown in section.

Fig. 2 is a horizontal sectional view, taken on the line 2—2 of Fig. 1, and

Fig. 3 is a side elevation of the lower portion of the machine.

The major portion of the herein described

machine, in accordance with the stated object to construct the same with rigid adherence to economy, is formed of wood of the proper kind, it being found that the latter material has the advantage of combining the necessary strength and lightness and lending itself admirably to structures of this character.

A supporting framework is provided comprising a pair of spaced uprights 1—1, which are appropriately connected to base sills 2—2, adapted to rest upon the floor or other support, and the said uprights are further supported in upstanding position by inclined braces 3—3, arranged in pairs and connected to each upright, as by pins 4—4, and adapted to rest upon said floor in front and in rear of the same, and thus preventing any tilting movement of the uprights, as clearly shown in Fig. 3 of the drawing.

The uprights 1—1 are connected, adjacent to their top ends, by a cross beam 5 which, like the uprights, the base sills and the braces, may be formed of wood and is suitably secured to said uprights by metallic brackets 6—6 bolted or otherwise fastened to the said beam and uprights.

The cross beam 5 is provided at a central point with a groove or slot 7 extending from one edge thereof to the longitudinal center line of the same, for a purpose to be explained, and is furthermore adapted to support a pair of brackets 8 and 9 respectively, in the form of castings, arranged in spaced relation to the said slot and suitably secured to the beam as by screws or bolts. The bracket 8 comprises a base portion for attachment to the beam and has an overhanging portion 10 adapted to overlie the slot 7 and provided with a socket 11 in its lower face in alinement with the said slot. The said bracket 8 also has an upstanding arm 12 located over the socket and provided with a transversely disposed bearing opening 13, which is in horizontal alinement with a similar bearing opening 14 provided at the upper end of the other bracket 9 located at the opposite side of the slot 7.

That upright or standard 1 located nearer to the bracket 9 is provided with a bearing opening 15 above the beam 5 and in alinement with the aforesaid bearings 13 and 14, and through these several bearings is adapted to be passed a horizontal shaft 16 which constitutes a power shaft when the

device is arranged to be driven by hand, as through the medium of a hand crank 17, indicated in dotted lines in Fig. 1 of the drawing.

5 A crown gear wheel 18 is suitably secured to the shaft 16 between the brackets 8 and 9, the teeth of said wheel facing toward the slot 7, and a pair of spools 19 and 20 are suitably mounted to rotate with the shaft 16 and arranged adjacent to the bracket 9 for the purpose of connection with the weight-driven mechanism to be later described.

15 A rectangular churn-body 21 of any desired capacity and formed of sheet metal, wood or crockery-ware is located beneath the beam 5, the center of the same being normally in vertical alinement with the socket 11 and the slot 7. The churn-body 20 21 is adapted to be supported by a pedestal 22, suitably secured thereto and resting upon a base 23 supported by the floor. The base 23 carries an upstanding pin 24 entering a suitable seat formed in the lower end 25 of the pedestal 22 and serves to prevent any lateral movement of the churn-body and pedestal relative to the said base. The base and pedestal may be formed of wood and are preferably provided with suitable anti-friction means, such as ball-bearings 25 to support the weight of the churn body and its contents and reduce the friction of the bearing to a minimum.

30 The churn-body 21 is provided with a suitable lid 26, hinged as at 27 to the rear edge of said body and having suitable clamps 28 for holding the same in position during the revolving motion of the body, and also provided with a sight opening 29 for the purposes of observing the progress of the churning operation.

35 A metallic tubular post 30, having an enlarged base portion 31 suitably secured to the center of the lid is adapted to extend 40 upwardly and through the slot 7 formed in the cross beam 5, and is provided at its upper end with a horizontally disposed gear wheel 32 preferably formed integral therewith and normally lying in meshing relation with the lower portion of the crown gear 18.

45 The lid 26 is provided with a centrally located aperture in alinement with the bore of the tubular post 30, and a vertically-disposed churn dasher shaft 33 is adapted to traverse the same and to extend somewhat above the gear wheel 32 and to be fitted into the socket 11 of the bracket 8, and to be held therein so as to prevent its 50 rotation, by a set-screw 34. As a further means for preventing the dislodgment of the tubular sleeve 30 from its position in the slot 7, a locking member 35, formed of suitable spring wire is secured to the beam 5, as at 36, at one side of the said slot 7

and extends across the latter and is adapted to engage behind an upstanding pin 37 located on the upper face of the beam 5 and thus surround the tubular sleeve 30 and confine the latter within said slot 7.

70 The shaft 33 carries at its lower end a dasher-hub 38 provided with a plurality of paddles 39 having the perforations 40 for permitting the passage of the milk within the churn-body 21, the said hub 38 being 75 detachably connected to the shaft 33 by a set-screw 41.

75 The construction and operation of the hand-driving means will be readily understood. When it is desired to churn a quantity of milk, the churn body 21 is removed from the frame of the machine, and the milk is placed within the body, the lid 26 being thrown back upon its hinges for the purpose: Then the dasher is secured upon 80 the inner or lower end of the shaft 33 through the medium of the set-screw 41: Next the lid is closed and locked upon the churn body 21 by means of the clamps 28, and the dasher and shaft are allowed to drop 85 when the dasher will rest upon the bottom of the churn-body, and the top of the said shaft 33 will project only slightly above the gear wheel 32, free to pass beneath the overhanging portion 10 of the bracket 8. 90 Upon sliding the churn body together with the base 23 into position, the shaft 33 may be elevated into position within the socket 11, and be secured therein by the set-screw 34 and the spring lock 35 engaged around 100 the tubular sleeve 30.

95 In order to adapt the machine for weight-driven means, the upper ends of the uprights 1-1 are each provided with mortises 42, into which are adapted to be fitted corresponding portions of extensions 43 which are of sufficient height to provide the necessary fall for the purpose designed. The upper ends of the extensions are provided with ball-bearing socket members 44 adapted to receive the end portions of a horizontally disposed shaft 45, preferably formed of a wooden bar, round for the major portion of its length and having a squared portion 46 arranged over the shaft 115 16, said squared portion having secured thereon, a pair of relatively large sheaves 47 and 48, located respectively over the spools 19 and 20 and connected therewith with reversely wound strands 49 and 50 respectively. Each of the strands 49 and 50, which may be of some suitable, strong, flexible cord or rope, are substantially equal in length to the height of the shaft 45 above the floor or support, and while the major portion of one strand is wound upon the proper sheave in one direction, the major portion of the other strand is wound upon its proper spool in the other direction, so that when a revolving motion is imparted to 130

the top shaft 45, in a manner to be described, it will readily be seen that one of the strands 49 or 50 will tend to rotate the shaft 16 in the same direction, while the other strand will be wound up upon either its sheave or spool, and in the opposite direction ready for the next operation of the device.

In order to impart rotary motion to the shaft 45, a pair of relatively small spools 51 and 52 are mounted upon the squared portion 46 thereof, near the adjacent extension 43 and have reversely wound thereon strands 53 and 54, each having at its free terminal a hook 55 for attachment to a suitable weight 56, one of the strands 53 or 54 being fully wound upon its proper spool while the other strand is extended its full length and extending nearly to the floor or support.

It will be readily seen that by engaging the weight to the end of the strand 53 or 54 located at the top of the machine, that the shaft 45 will be rotated in a direction depending upon the direction of winding of said strand, and that the shaft 16 will be correspondingly rotated by means of either the strand 49 or 50, and that the reverse of the operation is obtained by every alternate engagement of the weight 56 with the strands 53 and 54, so that practically a continuous operation of the machine may be obtained by merely changing the said weight.

By reason of the rectangular formation of the churn-body, the entire contents of the same is thrown against the stationary paddles 39, the perforations 40 formed in the same permitting the passage of some of the milk and resulting in the rapid breaking up of the fat cells therein, and the quick production of butter.

The following are the steps necessary to obtain access to the interior of the churn to remove butter therefrom, and clean the dasher, etc. First, the set screw 34 is loosened, which will permit the shaft 33 and its dasher to drop to the bottom of the churn. Then the latch 35 is disconnected, whereupon the sleeve 30 with its gear may be moved outwardly through the slot 7, and the churn itself with its base may be moved out of the way of the framework. Then the latch means 28 may be disconnected. The shaft 33 should now be pulled upwardly to bring the dasher 39 up against the under side of the lid 26. The lid may now be swung open without interference of the dasher with the sides of the churn, by taking advantage of the rectangular shape of the churn. With the lid once swung open, it is easy to disconnect the set screw 41,

whereupon the dasher may be removed from its shaft and the contents of the churn itself may be removed.

Obviously, my improved motor mechanism may be used to drive or rotate other things than churning, and while a churn has been described in some detail in connection with the invention, I do not wish my invention to be considered as being limited to such use.

What is claimed is:—

1. The combination with spaced uprights, an intermediate cross beam connecting the uprights, a body mounted for revolution between the uprights and having a closure, a spur gear carried by the closure and having a bearing in the cross beam, spaced brackets carried by the latter and having horizontally aligned bearings, a counter shaft mounted in said bearings and adapted to receive a hand crank and carrying a crown gear in normal meshing relation with the spur gear, a stationary shaft secured against rotation in one of the brackets and extending into the body, a pair of spools mounted on the countershaft, a shaft mounted at the top of the uprights and having a pair of sheaves in alignment with the said spools, strands reversely wound upon the sheaves and connected with the spools on the countershaft, a second pair of spools mounted on the top shaft and having reversely wound strands arranged thereon, and a weight for alternate connection to the last named strands for actuating the machine.

2. The combination with a gear-supporting frame-work including spaced upright standards carrying gearing including a pair of spools and a gear, a body mounted for rotation between the standards, a shaft extending within the body and secured against rotation to the frame-work, a gear carried by the lid of the body and adapted to be placed in meshing relation with the first-named gear, a shaft mounted at the top of the standards and having sheaves, strands reversely wound upon the same, and alternately extended and connected to the spools, a second pair of spools carried by the shaft and having strands secured thereto for alternate reverse winding thereon, and a weight for alternate connection to the last-named strands.

In testimony that I claim the foregoing as my own, I have hereto affixed my signature in the presence of two witnesses.

RAYMOND S. DEVNEY.
